Specification for Design.

Patented Oct. 8, 1918.

Application filed January 29, 1914. Serial No. 815,308. Term of patent 14 years.

To all whom it may concern:

Be it known that I, ALLEN P. WILSON, a citizen of the United States, residing at Waltham, in the county of Middlesex and State of Massachusetts, have invented a new, original, and ornamental Design for Chip-Receptacles for Pencil-Pointers, of which the following is a specification, reference being had to the accompanying drawing, forming part thereof.

Figure 1 is a side elevation of a chip receptacle showing my new design.

Copies of this patent may be obtained for five cents each, by addressing the "Commissioner of Patents, Washington, D. C."

Fig. 2 is a front end view of the same.

Fig. 3 is a rear end view.

I claim:

The ornamental design for a chip receptacle for pencil pointers as shown.

ALLEN P. WILSON.
